ABSTRACT

An electric mat switch assembly comprised of a multi-layer structure including a plurality of spaced metal contact plates having confronting contact surfaces and thin spacer means between the plates for normally maintaining said surfaces in closely spaced-apart relationship while permitting flexible movement into electrical engagement upon the application of pressure to the multilayer structure is provided with a layer of nonconductive nonvolatile fluid on at least one of said confronting contact surfaces. The fluid layer is a lubricating oil that adheres to the contact surface and suspends insulating metal oxide particles from the surfaces of the plates to impart increased mobility thereto for permitting electrical contact between the contact plates when the surfaces are compressed into intimate engagement.

SHEET 1 OF 2

FIG. 3

MAT SWITCH WITH CLEANING OIL FILM

BACKGROUND AND SUMMARY OF THE
INVENTION

The present invention relates to mat switches for controlling the operation of electrically actuated doors and the like. More particularly it relates to a new mat switch construction having improved response characteristics to pressure applied thereto by pedestrian traffic moving thereacross.

As is well known, mat switches of the type described generally are multi-layer sandwich assemblies comprised of several flexible metal plates maintained in normally closely spaced-apart relationship by thin non-conductive separators. The separators are configured to permit the uppermost metal plate to be depressed and the plates squeezed together by the weight of pedestrian traffic moving over the top surface of the mat. It is important for the proper operation of mats of this type that the pressure sensitivity thereof be maintained between certain predetermined pressure levels. If the responsive pressure level is set too high, grocery carts or small children would not actuate the door and accidents could result. Alternatively, an excessively low pressure response level could result in unnecessary and unwanted operation of the door controlled by the mat switch.

The metal plates in the mat assembly are thin enough to be flexible and resilient and are constructed of suitable conductive materials such as sheet aluminum and the like. Although the mat switch is conventionally sealed about the periphery thereof, a limited degree of oxidative corrosion occurs on the planar contact surfaces of the plates and, in the case of aluminum, insulative oxides that reduce the conductivity sensitivity of the contact plates tend to form thereby adversely affecting the contact pressure required to effect dependable operation of the electrically-actuated doors controlled by the electric mat switch. For example, a mat switch having a minimum pressure load sensitivity of about 20 pounds when initially constructed and installed may lose its sensitivity over a period of one to two years so that a load of 50 pounds is required to effect its operation. As can be appreciated, this difference can be important particularly where the pedestrian traffic includes small children whose weight may not be sufficient to apply the requisite pressure to the mat. Additionally, the thin metal oxide layer tends to granulate and fall off the plates. These granular particles tend to cause accelerated abrasive wear of the assembly and can "cake" to render isolated areas fully inoperative.

Accordingly, it is an object of the present invention to provide a new and improved electric mat switch assembly having a stabilized and more uniform sensitivity over prolonged periods of operation.

Another object of the present invention is to provide a mat switch of the character described that exhibits not only a stabilized pressure sensitivity but also is subject to reduced wear characteristics thereby further enhancing the operating life of the mat.

Still another object of the present invention is to provide a new and improved mat switch assembly that reduces the formation of metal oxides and prevents the compacting thereof that might otherwise reduce the sensitivity of the plate and reduce the wearability thereof. Included in this object is the provision for the

foregoing advantages in a low-cost economical manner that lends itself readily to mass-production techniques.

A further object is to provide a mat switch having means for maintaining solid oxidative products in a mobile condition so as to reduce their tendency to affect the sensitivity of the switch assembly. Included in the object is the provision for fluid capable of suspending dust particles located between the contact surfaces of the switch without hampering the desired electrical performance of those surfaces and in fact improving such performance, such as by acting as a spark depressant.

Other objects will be in part obvious and in part pointed out in more detail hereinafter.

These and related objects are accomplished in accordance with the present invention by providing an electric mat switch assembly comprised of a multi-layer structure including a plurality of spaced metal contact plates having confronting contact surfaces, thin spacer means between the plates for normally maintaining said surfaces in closely spaced-apart relationship while permitting flexible movement into electrical engagement upon the application of pressure to the multi-layer structure and a layer of nonconductive nonvolatile fluid on at least one of said confronting contact surfaces. The fluid layer adheres to the contact surface and suspends metal oxide particles between the plates to impart increased mobility thereto for permitting electrical contact between the contact plates when the surfaces are compressed into intimate engagement.

A better understanding of the objects, advantages, features, properties and relationships of the invention will be obtained from the following detailed description and accompanying drawing which set forth an illustrative embodiment and are indicative of the way in which the principles of the invention are employed.

A BRIEF DESCRIPTION OF THE DRAWING

In the drawings:

FIG. 1 is a perspective view partially broken away and partially in section illustrating a mat switch assembly incorporating the features of the present invention;

FIG. 2 is an enlarged sectional view taken along the line 2—2 of FIG. 1 with some of the layers of the multi-layer structure exaggerated in size for illustrative purposes and;

FIG. 3 is a still further enlarged sectional view of a portion of a mat switch embodying the features of the present invention.

DESCRIPTION OF A PREFERRED EMBODIMENT

Referring now to the drawings in greater detail wherein like reference numerals indicate like parts throughout the several figures, mat switch 10 is shown as comprised of a three-conductor plate multi-layer assembly of the general type described in U.S. Pat. No. 2,700,080 with a modified spacer construction. The contact plate assembly 12 of the switch 10 is enclosed in a suitable weather-proof envelope of rubber or the like consisting of a base layer 14 and a top layer 16 that is provided with a corrugated top surface 18 in a conventional manner to provide a wear-resistant tread for the mat switch. The contact plate assembly 12 is best shown in FIG. 2 as consisting of a top plate 20 firmly adhered to the underside of the weather-proof tread layer 16 and a lower or bottom contact sheet 22 resting on the base layer 14 and electrically connected to the

top plate 20 by means of a suitable rivet assembly or the like (not shown) and to a first common lead of the electrical terminal 24. The intermediate or middle contact plate 26 is sandwiched between the upper and lower plates, 20, 22 and is electrically connected to a second lead of the terminal 24 so that contact between plate 26 and either plate 20, or 22 will effect a closed circuit condition.

Adjacent plates of the contact assembly 12 are separated by pieces of insulating material preferably formed as integral thin sheets of non-conductive material provided with a plurality of apertures spaced at regular intervals to permit electrical contact between the intermediate switching plate and either the top or bottom contact plates. In the particular embodiment illustrated, the insulating material is shown as taking the form of a pair of insulating sheets on opposite sides of the switching plate 26. Thus the spacer array between plates 26 and 20 includes a pair of sheets having apertures that are in registry but are of different size to form a step-wise construction reducing the amount of flexing or bending required by the contact and switching plates in order to provide the desired closed circuit condition. Thus, as best shown in FIG. 1, the uppermost sheet-like spacer, which may be of thin non-conductive material such as heavy paper or the like, is preferably cut to form a stencil having a plurality of rectangular strips 30 extending across the sheet in spaced parallel relationship. The second spacer in the array immediately adjacent the middle switching plate 26 is of similar construction except that the rectangular strips 32 formed therein are substantially narrower but are in registry with the overlying broader strips 30 in order to provide the step-wise configuration mentioned hereinbefore.

A similar spacer array is provided between the central contact plate 26 and the lower contact plate 22 except that the lower spacers are arranged in mirror image fashion relative to the top spacers 30, 32 and are offset therefrom. Thus the lowermost spacer adjacent plate 22 is provided with the broad rectangular strips 34 while the lower spacer closest to the center contact plate 26 is provided with the narrower rectangular strips 36. Additionally, the lower spacer array is laterally spaced relative to the upper spacer assembly so that the rectangular transversely extending strips 34, 36 are disposed intermediate the rectangular strips 30, 32 in the upper array. As will be appreciated, this staggered or laterally displaced arrangement will facilitate a more gradual deflection under pressure in the upper or middle plates in order to make the necessary electrical contact therebetween.

As mentioned hereinbefore, the metal contact plates are generally subject to oxidative corrosion and in the case of the aluminum sheet material used for the contact plates, an aluminum oxide is formed. The aluminum oxide exhibits an electrically insulating character which tends to interfere with the desired electrical contact between the contact plates. Additionally, the aluminum oxide is an abrasive material which cuts away at the paper spacers and abrasively wears the contact plates themselves. This abrasive insulating dust formed within the weather-proof rubber envelope can rapidly and seriously interfere with the operation of the mat switch.

In accordance with the present invention, the formation of the undesirable oxide film is substantially reduced and the oxide which is formed is maintained in

a flowable or suspended condition so as not to cause abrasive wear or interfere with the desired contact between the contact plates of the mat switch assembly. This is accomplished by coating the contact plate with a thin coating of a viscous non-conductive liquid capable of forming an adhering film on the surfaces of the plate while suspending oxide particles therein and permitting intimate electrically conductive surface contact between the contact plates when they are pressed into engagement by pedestrian traffic applying pressure to the top tread surface 18 of the mat.

The liquid found most suitable for this purpose is a mineral oil readily adapted to application by roller coating techniques. In the assembly 10 used for illustrative purposes the mineral oil is applied to both sides of the center contact plate 26 and is designated by the numerals 38, 40 (see FIG. 3). Of course, as will be appreciated, the oil is picked up by the top and bottom plates during use of the mat. However, initially, it is only necessary that the coating be applied to the central plate 26 in order to provide the desired stabilized sensitivity characteristics. In this regard, electrical mat switches incorporating the coated oil on a contact plate thereof have shown no substantial increase in the minimum pressure value required to affect contact, even after prolonged service conditions. In fact, mats produced in accordance with the present invention have tended to exhibit a stabilized pressure value required for a closed-circuit condition. This is to be compared with a conventional increase experienced heretofore of about 100% in the minimum pressure value for a period of about one to 2 years.

The liquid employed is preferably of medium viscosity, i.e. between about 150 to 500 seconds Saybolt at 100°F and when applied by a roller coater, results in a surface adhering film having a thickness of about two to six mils. As will be appreciated, the liquid should be substantially free of highly volatile components and should be relatively stable over wide temperature conditions in view of the fact the electric mat switch may be placed in a location subject to seasonal temperature changes or may be placed in environments where the temperatures will vary substantially. Among the primary requirements of the oil are its ability to adhere readily to the surface to which it is applied as a thin coating and to suspend the small granular metal oxides formed on the surface of the contact plates. The suspended granules designated by the numeral 42 can then more readily flow away from the area of contact between the adjacent plates as the plates are compressed into engagement. This reduces the interference to electrical contact and providing a more stabilized sensitivity in the mat over a prolonged work life. Additionally, the oil should be substantially insulative in character and capable of readily flowing so as to permit engagement between the contact plates when pressure is applied to the top of the mat.

Although a number of different high quality mineral oils for lubricating machinery bearings or the like may be employed, one specific oil that has been used with good results is a paraffinic straight mineral machine and engine oil sold by Atlantic Richfield Company under the trademark "Rubilene S-315". This material has a viscosity of 310 seconds Saybolt at 100°F and 53 seconds Saybolt at 210°F with a viscosity index of 95. It has a carbon residue of only 0.05 percent by weight and exhibits a flash temperature of 430°F.

The oil not only functions to suspend the insulating granular or powdered material formed on the contact plates but also acts as a lubricant to resist wear between the contact plates and the insulating spacers whereby further enhancing and prolonging the operating life of the carpet. The effectiveness of the oil is particularly surprising since many electrical systems employing contacts will not operate effectively when the contact surfaces are coated with a nonconductive oil. However, in the present invention the oil tends to disperse in conductive granules so as to stabilize the operation of the contact plates, remove oxides therefrom and act as a spark depressant. The oil provides an environment which prevents buildup or caking of the insulative aluminum oxides on the contacts and tends to insulate the contact surface from the air sealed within the assembly.

As will be appreciated by persons skilled in the art, various modifications, adaptations and variations of the foregoing specific disclosure can be made without departing from the teachings of the present invention.

I claim:

1. An electric mat switch comprised of a multi-layer structure including a plurality of spaced metal contact plates having confronting contact surfaces subject to the formation during use of granular metal oxide particles that can reduce the pressure sensitivity of the plates, thin spacer means between the plates for normally maintaining said surfaces in closely spaced-apart

relationship while permitting flexible movement into electrical engagement upon the application of pressure to the multi-layer structure, said flexible movement being sufficient to cause said granular particles to become loosened from the contact surfaces, and a layer of nonconductive nonvolatile fluid on at least one of said confronting surfaces, said fluid layer being firmly adhered to the contact surface and uniformly suspending said loosened granular particles and imparting mobility thereto, said layer permitting electrical contact between said contact plates when said surfaces are moved into intimate engagement and maintaining a stabilized pressure sensitivity in the switch over a prolonged period of use.

15 2. The mat switch of claim 1 wherein the fluid is a medium viscosity liquid.

3. The mat switch of claim 1 wherein the fluid is a mineral oil.

4. The mat switch of claim 1 wherein the fluid layer 20 has a film thickness of about two to six mils.

5. The mat switch of claim 1 wherein the multilayer structure includes three metal contact plates and the planar surfaces of the intermediate contact plate each carry a layer of the nonconductive liquid.

25 6. The mat switch of claim 5 wherein the liquid is a paraffinic oil having a viscosity up to about 500 seconds Saybolt at 100°F.
